UNITED STATES PATENT OFFICE

157,031

COMBINED CAMISOLE AND SLIP

Harry Colton, New York, N. Y.

Application May 6, 1948, Serial No. 146,197

Term of patent 3½ years

(Cl. D3—26)

To all whom it may concern:

Be it known that I, Harry Colton, a citizen of the United States of America, residing in New York, county of New York, and State of New York, have invented a new, original, and ornamental Design for a Combined Camisole and Slip, of which the following is a specification, reference being had to the accompanying drawing, forming part thereof.

Fig. 1 is a front view of a combined camisole and slip showing my new design.

Fig. 2 is a rear view thereof.

I claim:

The ornamental design for a combined camisole and slip, substantially as shown.

HARRY COLTON.
